PROPELLION MECHANISM FOR AIRCRAFT

Richard H. Burgess, San Antonio, Tex.

Application May 27, 1936, Serial No. 82,119

5 Claims. (Cl. 244—72)

This invention relates to an improved propulsion mechanism for aircraft, being especially designed for use in conjunction with aeroplanes and gliders.

5 Among other objects, the invention seeks to provide a wing tip which may be oscillated, either manually or by power, relative to the body of the wing for propelling the aircraft forwardly with the greatest efficiency in proportion to the 10 effort expended.

A further object of the invention is to provide a wing tip composed of a plurality of parallel blades and wherein said blades will be so constructed and mounted that as the wing tip is 15 swung upwardly, the blades will yieldably deflect downwardly to act on the air for driving the aircraft forwardly while, as the wing tip is swung downwardly, the blades will yieldably deflect upwardly to act on the air for a like purpose.

20 And the invention seeks, as a still further object, to provide a wing tip of unique and novel construction.

Other and incidental objects of the invention not specifically mentioned in the foregoing 25 will appear during the course of the following description and in the drawing which forms a part of my application,

Figure 1 is a plan view of my improved mechanism.

30 Figure 2 is an enlarged detail sectional view showing the construction of the blades of the wing tip.

Figure 3 is a transverse section through one of the blades and showing the manner in which the 35 blades are adapted to be deflected both upwardly and downwardly.

Figure 4 is a detail section showing the levers for rocking the wing tip.

Figure 5 is a fragmentary section showing a 40 slightly modified form of blade.

Figure 6 is an enlarged detail section of the modified structure.

Referring now more particularly to the drawing, I have shown the body of an aeroplane or 45 glider wing at 10. The wing body may be of any approved construction and is straight at its outer end.

Mounted to swing up and down relative to the wing body 10 at the outer end thereof is a 50 wing tip. This wing tip comprises a hinge rod or header 11 from which projects a plurality of spaced parallel lateral studs 12 and fixed to said studs are blades 13 slightly spaced apart and all normally lying in the same plane.

55 Each of the blades 13 includes a flexible re-

silient stem 14 looped at its free end portion to provide a substantially U-shaped frame 15 and slipped over said frame from the outer end thereof is a bag of canvas or the like forming a web 16. The bag is closed at its outer end and will be held taut by the resiliency of the frame 15, the overlapping thicknesses of the bag being cemented together by dope which will also serve to secure the web on the frame. While any approved material may be employed still, the stems 14 are each preferably formed of a length of bamboo cored out at its larger end and slipped over one of the studs 12 to which the length of bamboo is suitably fixed. This construction is light in weight and the bamboo possesses the 15 necessary strength, toughness and resiliency. Extending between the stems near their inner ends is an appropriate brace rod 17.

If preferred, a straight length of bamboo may be employed to form a stem 18 and fixed to said stem at spaced points are loops 19 of resilient wire. These loops are provided with studs 20 which extend through the stem and securing the loops to the stem are cotter pins 21. The several loops provide a frame which carries a web 25 22 like the webs 16.

Projecting from the outer end of the wing body 10 are spars 23 to which the rod 11 is hingedly connected in any appropriate manner and extending laterally in opposite directions from said rod are levers 24. Attached to said levers are cables 25 which extend into the fusilage of the aircraft and may be operated manually or by power for swinging the wing tip up and down. As the wing tip swings upwardly, downward 35 canting of the webs 16 of the blades 13 will be resisted by the stems 14 of said blades but the webs will, however, be deflected by the air and move into a downward angular position to act on the air for propelling the aircraft forwardly. 40 Similarly, as the wing tip swings downwardly, the webs 16 of the blades will be deflected into an upward angular position for propelling the aircraft forwardly so that both the upward and downward movement of the wing tip will be utilized 45 for driving the aircraft ahead.

Having thus described the invention what I claim is:

1. Propulsion mechanism for aircraft including in combination with a wing body, a wing tip 50 hinged to the wing body and composed of a plurality of blades including flexible stems provided with lateral webs, the stems being resiliently twistable to torsionally resist but yield to both upward and downward deflection of the webs by 55

the air as the wing tip is swung, and means for swinging said tip.

2. Propulsion mechanism for aircraft including a header, flexible resilient stems carried by the 5 header and looped to form U-shaped frames each having a single leg thereof fixed to the header, envelops fitting over said frames and providing blades having webs extending laterally from the stems, the several blades forming a wing 10 tip, means for hingedly connecting said tip with a wing, and means for swinging said tip.

3. Propulsion mechanism for aircraft including a rod having spaced studs extending therefrom to form a header, flexible resilient stems fixed to 15 said studs and looped to form frames each having a single leg thereof engaged with one of said studs respectively, fabric bags engaged over said frames and forming blades having webs extending laterally from said stems, the several blades 20 forming a wing tip, means for hingedly connecting said tip with a wing, and means for swinging said tip.

4. Propulsion mechanism for aircraft including a wing body, a plurality of double-acting blades hinged at the outer end of the wing body to form a swingingly supported wing tip, the blades being spaced to freely and individually 5 twist downwardly as the wing tip is swung upwardly and upwardly as the wing tip is swung downwardly and being torsionally resilient for exerting a forward propelling force on both the upward and downward movement of the wing 10 tip, and means for swinging said tip.

5. Propulsion mechanism for aircraft including a plurality of blades, means supporting the blades to swing as a unit, said blades being spaced to freely and individually twist downwardly as the 15 blades are swung upwardly and upwardly as the blades are swung downwardly and being torsionally resilient for exerting a forward propelling force on both the upward and downward swinging movement of the blades, and means for 20 swinging the blades.

RICHARD H. BURGESS.
